United States Patent Office.

GEORGE CUSTER, OF MONROE, MICHIGAN.

Letters Patent No. 101,831, dated April 12, 1870.

IMPROVEMENT IN TOE-CALK FOR HORSESHOES.

The Schedule referred to in these Letters Patent and making part of the same.

To all whom it may concern:

Be it known that I, GEORGE CUSTER, of Monroe, in the county of Monroe and State of Michigan, have invented a new and valuable Improvement in Toe-Calks for Horseshoes; and I do hereby declare that the following is a full, clear, and exact description of the construction and operation of the same, reference being had to the annexed drawings making a part of this specification, and to the letters and figures of reference marked thereon.

Figure 1 of the drawings is a representation of a vertical section of my invention.

Figure 2 is a top view of the same.

Figure 2 is a front view thereof.

My invention relates to horseshoes, and consists in the construction and novel arrangement of a secure toe-calk, designed to be welded to the front of the shoe, and arranged to take the proper forward set or inclination when thus welded.

The letter A of the drawings designates my toe-calk, a curved bar of cast-steel or other suitable metal. Its upper surface e is somewhat beveled forward and downward, and rising from it is a central spur or projection, c.

This spur or projection is flattened from front to rear, and while its rear face is flush with the rear wall of the calk, the front face joins the beveled upper surface at about the center, the object of this arrange-

ment being that when the calk is driven into the shoe, its front shall be flush with the front thereof.

At each side of the wedge or spur near its base are formed notches a a, thus giving the spur a neck, as it were, and in the welding process the hot iron contracts about this neck, thereby forming a firm and secure fastening.

If the single wedge does not give the required strength, two or more may be employed.

I do not desire to confine myself to the number of fastening spurs, nor to the precise form thereof, but I am aware that toe-calks with spurs upon their upper sides, the said upper sides being without bevel, as shown in the patent of Charles H. Perkins, April 9, 1861.

I do not claim such, but

What I claim as my invention, and desire to secure by Letters Patent, is—

The toe-calk for horseshoes herein described, having its upper edge beveled and provided with the spurs or pointed wedges c, having notches a a at each side, when constructed as and for the purposes specified.

In testimony that I claim the above, I have hereunto subscribed my name in the presence of two witnesses.

Witnesses:

J. R. RAUCH,
I. R. GROEMAN.
